UNITED STATES PATENT OFFICE.

TIMOTHY TRURAN, OF MIDDLESBORO, BRITISH COLUMBIA CANADA.

AUTOMATIC ENGINE-STOP.

1,109,373.

Specification of Letters Patent.

Patented Sept. 1, 1914.

Application filed August 2, 1913. Serial No. 752,749.

To all whom it may concern:

Be it known that I, TIMOTHY TRURAN, a subject of the King of Great Britain, and a resident of Middlesboro, British Columbia, Canada, have made certain new and useful Improvements in Automatic Engine-Stops, of which the following is a specification.

My present invention relates to automatic engine stops, and my object is to provide a simple and effective arrangement by which to shut off an engine supply valve in connection with rope drives, and for actuation where the rope is broken and also where either a splice pulls out or the rope slacks to such an extent as that it might jump its proper groove and cause serious trouble.

With the above in mind my invention resides in the features of construction, arrangement and operation to be now described in connection with the accompanying drawings, forming a part of this specification, and in which—

Figure 1 is a side elevation. Fig. 2 is an end elevation. Fig. 3 is a detail section taken on line 3—3 of Fig. 1, and, Fig. 4 is a similar view taken on line 4—4 of Fig. 1.

Referring now to these figures, A indicates the usual grooved drum into the grooves of which is wound the operating rope B, the drum being actuated by an engine of suitable character. I have here shown the operation engine in the ordinary form of reciprocating steam engine with a supply pipe C' in which is disposed a cut-off valve C² in addition to the usual throttle valve.

In accordance with my invention one end of a valve controlling lever D is secured to a shaft d above that portion of the operating engine farthest removed from the drum A, this shaft being journaled horizontally in brackets d' and having an arm E extending substantially parallel with the lever D and connected to the cut-off valve of the engine before mentioned by means of a vertically movable connecting rod E' which is preferably adjustable in length. Thus with the lever D raised and in its normal position, the cut-off valve of the engine is held open. Depending from points above opposite sides of the drum A are a pair of tubular rods F and F', the upper ends of which are pivotally mounted in brackets f and f' respectively, so that they may swing in the direction of movement of

the cable B and the lower ends of which are provided with set screws f² whereby to adjustably secure the legs of a U-shaped bar G therein. As will be seen, the cross piece of the U-shaped bar G extends across the face of the drum A and may be adjusted toward and away from the same as desired, the tubular supports F and F' and the U-shaped bar G forming a pivoted tilting frame which may be swung in either direction whenever the operating rope B parts or slacks to a sufficient degree. Depending along side of the tubular rod F is a bar H, the upper end of which is pivoted in the bracket f as shown in Fig. 2, and the lower end of which is connected with said rod F by means of a stud h on which is journaled a roller h'.

As particularly shown in Fig. 1, the lever D is provided adjacent its outer free end with a depending extension D' which in the normal position of the parts rests upon the roller h', the said free end of the lever D extending between the upper end of the bar H and the tubular support F as particularly shown in Fig. 2. Thus it will be seen that should the operating rope B part either by pulling out a splice or by breaking between splices the broken strands will necessarily strike the tilting frame and move the same over to one side or the other. It will be further seen that any such movement of the tilting frame will result in moving the roller h' from beneath the lever extension D' and that as a result the said lever will swing downwardly and lower the cut-off valve to closed position, these movements being apparent by reference to and comparison of the full and dotted positions shown in Fig. 1.

By virtue of the fact that the U-shaped bar G is adjustable in its tubular supports F and F', it will be seen that the tilting frame may be adjusted to a selected position with respect to the drum A in order that the stopping mechanism may be regulated to operate if there is sufficient slack in the operating rope to cause the same to jump a groove of the drum.

It will be seen that my improved mechanism is simple, may be readily installed in connection with rope drives now in use and will be durable and effective in operation.

I claim:

1. The combination with a drive rope drum and its power mechanism, the latter

being provided with a cut-off, of a trip lever pivoted at one end and having connection with the cut-off and provided with a depending extension at its opposite end, and 5 a U-shaped frame pivotally supported with its lower cross bar transversely above and in close proximity to the rope drum to swing in the direction of movement of the rope, said frame consisting of depending 10 tubular rods and a U-shaped bar having its legs adjustably secured in the lower ends of the said supports, and a roller carried by the frame and normally supporting the depending extension of the trip lever, all for the 15 purpose described.

2. The combination with a drive rope drum and its power mechanism, the latter of which is provided with a cut-off, of a trip lever pivoted at one end above the 20 power mechanism and having connection adjacent its pivoted end with the cut-off, and a frame pivotally supported transversely above the drive rope drum and provided with a cross bar adjacent to said drum

and adjustable toward and away from the 25 same said frame normally forming a direct support for the free end of the trip lever and being movable in the direction of movement of the rope, all for the purpose described. 30

3. The combination with a drive rope drum and its power mechanism, the latter of which is provided with a cut-off, of a swinging frame movable in the direction of movement of the rope and having a cross 35 bar adjacent to and transversely above the drum, a trip lever pivoted at one end above the power mechanism and having its free end normally disposed directly on and supported by the said swinging frame, and an 40 operative connection between the said trip lever and the cut-off of the power mechanism, all for the purpose described.

TIMOTHY TRURAN.
